UNITED STATES PATENT OFFICE.

ALEXANDER THOMSON, OF FITCHBURG, MASSACHUSETTS.

SAFETY-TRACE CONNECTION.

1,241,304.

Specification of Letters Patent. Patented Sept. 25, 1917.

Application filed January 18, 1916. Serial No. 72,712.

To all whom it may concern:

Be it known that I, ALEXANDER THOMSON, a citizen of the United States, and a resident of Fitchburg, in the county of 5 Worcester and State of Massachusetts, have invented a certain new and useful Improvement in Safety-Trace Connections, of which the following is a specification.

My present invention relates generally to 10 trace connections, and more particularly to a trace connection particularly adapted for use in connection with metallic collars, of that nature now commonly used in fire, artillery, and other heavy harness of like 15 nature, my object being to provide a connection which may be quickly and effectively made and which, when effected, will defeat all tendency of the parts toward relative displacement.

20 A further and more specific object of my invention is to provide a trace connection of the hook-and-eye type, which will be movable and flexible in engaged position, and at the same time, by its particular construction, defeat any tendency toward separation of the connected parts.

The above objects are preferably carried out through the particular arrangement to be now described in connection with the 30 accompanying drawing illustrating my invention and forming a part of this specification, and wherein—

Figure 1 is a front view, partly in section, illustrating the hook in its position of 35 initial engagement with the fastening eyes.

Fig. 2 is a similar view illustrating the hook in inverted position constituting the second movement toward complete engagement of the parts.

40 Fig. 3 is a perspective illustrating the parts in complete operative engagement.

Fig. 4 is a detail section through the engaged hook and eye taken substantially on line 4—4 of Fig. 3.

45 Fig. 5 shows the application of the fastener to a hame, and

Fig. 6 is a section taken on line 6—6 of Fig. 5.

Referring now to these figures, the fastener A includes a plate as seen which may be secured in any suitable manner upon the part intended as its support, for instance, a metallic horse collar a portion of one side of which is generally indicated at B in Figs. 50 55 1 to 3 inclusive, the plate of the fastener having an outstanding eye A', the particu-

lar construction of which forms in part the present invention. This eye, it will be noted, has one side portion A², the cross section or diameter of which is considerably 60 less than that of the other side portion A³ as may be most plainly seen by reference to Figs. 1 and 2.

The hook C, which constitutes the other part of the invention, may have any suitable means as indicated at C', providing for the attachment of the trace tug or other connection D which it is intended to support, and its hook end is provided with an inner eye portion C² and a throat portion C³ 70 communicating with the said eye portion and of substantially less width than the diameter of the eye portion.

For the proper engagement of the hook C with the eye A', the eye portion C² of the 75 hook is sufficiently large to receive the thickened side portion A³ of the eye A', while the reduced throat portion C³ of the hook is of less width than the diameter of the thickened portion A³ of the eye A', but is sufficiently wide to receive the reduced side portion A² of the eye A'.

Thus in engaging the hook with the eye, it is necessary to initially move the throat portion C³ onto the smaller side portion A² 85 of the eye, as seen in Fig. 1, and, after reaching the eye portion C² of the hook, invert the hook to the position shown in Fig. 2, the eye portion of the hook accommodating the thickened side portion A³ of the 90 eye. The entire hook may be then turned to extend in the proper direction from the eye, and the parts are in full operative engagement as shown in Fig. 3, from which it will be seen that the reduced throat portion 95 C³ of the hook precludes all danger of relative displacement.

Thus it will be seen that I am not only enabled to provide a connection of this character eliminating all danger of relative displacement of the connected parts, but I am also enabled to do this without sacrificing any of the usual advantages of such a connection, and without sacrificing in any respect whatever, the natural strength, durability, and effectiveness of connections of like character as ordinarily constructed.

It is apparent upon inspection of Fig. 3 that, even should the lower portion of the hook engaged in proper position be moved 110 outwardly due to any cause whatever, a movement which gravity would tend to de-

feat, there is still little danger of displacement of the hook from the fastening eye, but to defeat such a movement, the lower enlarged side A³ of the eye A', may be provided with an enlargement indicated at A⁴ in Figs. 3 and 4, engaging one side of the hook when the latter is in operative position as shown in Fig. 3, and tending to defeat the same.

- 10 While I have shown and described the fastener in connection with metallic horse collars, it is equally applicable to, and intended to operate the same in connection with, a hame E as shown in Figs. 5 and 6, 15 by slight change of the plate F supporting the eye F' in regard to its particular shape and mode of fastening. The hook G may

also have a shank G' riveted or otherwise secured to the trace H.

I claim:—

20 A safety connection of the character described, comprising a hook having a reduced throat portion, and a fastener having an outstanding eye thickened at one side for engagement in operation by the hook, and 25 having a relatively thin opposite side for reception by the reduced throat portion of the hook when the latter is inserted in place, the said thickened side portion of the said eye having an enlargement engaging one 30 side of the hook in operative position to prevent upward swinging movement of the hook in the eye.

ALEXANDER THOMSON.
